UNITED STATES PATENT OFFICE.

JOHN HOWARD, OF ULYSSES, NEBRASKA.

TOBACCO-CUTTER.

1,261,537.

Specification of Letters Patent.

Patented Apr. 2, 1918.

Application filed July 18, 1917. Serial No. 181,336.

To all whom it may concern:

Be it known that I, JOHN HOWARD, a citizen of the United States, residing at Ulysses, in the county of Butler and State of Nebraska, have invented new and useful Improvements in Tobacco-Cutters, of which the following is a specification.

This invention relates to cutters especially adapted to be used for severing plug tobacco and it consists in the novel features hereinafter described and claimed.

An object of the invention is to provide a cutter of the character stated which is of simple and durable structure and which may be used upon a counter or other support for cutting a plug of tobacco into sections.

With this object in view the cutter comprises a base upon which is mounted a frame with a lever pivoted thereon. A shaft is mounted for vertical movement upon the frame and a link operatively connects the said shaft with the lever. A blade is rotatably mounted upon the shaft and guided between the side portions of the frame. The said blade is preferably rectangular in side elevation and is provided with angularly disposed cutting edges. Spaced lugs are carried at one side of the blade. Combined scrapers and sharpeners are attached to the same and bear against the opposite sides of the blade at the edge thereof. An arm is pivotally mounted upon the frame and is provided with a crotch which is adapted to receive the lugs when the blade is elevated and partially turn the same.

In the accompanying drawings:—

Figure 1 is a side elevation of the tobacco cutter;

Fig. 2 is a top plan view of the same;

Fig. 3 is a side elevation of the cutter viewing the same at the opposite sides from that shown in Fig. 1.

Fig. 4 is a fragmentary sectional view of the cutter.

Fig. 5 is an end view of the same.

The tobacco cutter comprises a base 1 which may be made of wood or any other suitable material. A frame is mounted upon the base 1 and the frame comprises standards 2 and standards 3. The standards are arranged in pairs and the corresponding members of the pairs of standards are connected together by means of cross bars 4. The standards 3 are somewhat taller than the standards 2. A lever 5 is pivoted between the upper ends of the standards 3.

Spaced guides 6 are located at one side of the said frame and are connected at their upper ends with one of the bars 4. The lower ends of the guides 6 are connected by 60 means of a bar 7 with one of the standards 2. A shaft 8 is mounted for vertical movement between the guides 6 and a link 9 is pivotally connected at one end with the said shaft 8 and pivotally connected at its other 65 end with the lever 5. A blade 10 is rotatably mounted upon the shaft 8 and is located between the opposite sides of the said frame. The said blade 10 is preferably rectangular in side elevation and is provided 70 with angularly disposed cutting edges. Combined cleaners and sharpeners 11 are secured to the standards 3 and the lower portions of the said cleaners and sharpeners are inwardly disposed and bear against the 75 opposite sides of the blade 10 at the edge thereof. An arm 12 is pivoted to one of the standards 3 and extends in a downward direction along one side of the blade 10. The arm 12 is provided in the vicinity of its 80 lower end with a crotch 13 which is adapted to receive successively lugs 14, the said lugs being located upon the side of the blade 10 and spaced from each other and spaced at equal distances from the center of the said 85 blade.

When the free end of the lever 5 is swung in an upward direction, one of the lugs 14 upon the blade 10 will enter the crotch 13 of the arm 12 and as the blade 10 and the 90 shaft 8 are moved in an upward direction by the link 9 the said arm 12 will turn the blade 10 upon the shaft 8 so that the edge of the blade 10 which was previously vertically disposed will be moved to a horizontal position 95 between the opposite sides of the frame. Consequently the edge of the blade 10 which previously was in a horizontal position is carried between the cleaners and sharpeners 11 and any material which might have accumulated upon the said cutting edge is removed therefrom and the said edge is subjected to an abrading action which has a tendency to sharpen the same.

The plug of tobacco which is to be cut is 105 placed upon the base 1 below the blade 10 and then the lever 5 is swung in a downward direction whereby the link 9 moves the shaft 8 in a downward direction and the blade 10 is carried down so that its lower 110 edge is caused to penetrate the plug of tobacco and cut a section therefrom.

From the foregoing description taken in conjunction with the accompanying drawing, it will be seen that a plug tobacco cutter of simple and durable structure is provided, and that the same is automatic in its action in maintaining the blade thereof in a clean and sharp condition.

Having described the invention what is claimed is:—

10. A tobacco cutter comprising a frame, a lever pivoted thereon, vertically disposed

guides carried by the frame, a shaft mounted for movement between the guides, a link operatively connecting the shaft with the lever, a blade journaled upon the shaft, lugs carried at the side of the blade, and an arm pivoted to the frame at the pivot of the lever and provided with a crotch adapted to receive the said lugs successively.

In testimony whereof I affix my signature.

JOHN HOWARD.
